UNITED STATES PATENT OFFICE.

GEORGE IBACK, OF DETROIT, MICHIGAN.

CONCRETE REINFORCEMENT.

No. 851,169.

Specification of Letters Patent.

Patented April 23, 1907.

Application filed April 20, 1906. Serial No. 312,868.

To all whom it may concern:

Be it known that I, GEORGE IBACK, a citizen of the United States, residing at Detroit, in the county of Wayne and State of Michigan, have invented new and useful Improvements in Concrete Reinforcement, of which the following is a specification.

The invention is a reinforced concrete structure designed particularly for use as a beam, girder, or arch, and the object of the invention is to provide an improved form of metal reinforcement which will be embedded in the concrete and serve to increase the strength and rigidity thereof as well as to bind the concrete together, and thereby increase its structural strength.

An embodiment of the invention is illustrated in the accompanying drawing, in which

Figure 1 is a central longitudinal section of a beam provided with the reinforcement. Fig. 2 is a side elevation of the reinforcing bar and attachments, removed from the concrete. Fig. 3 is an end elevation of the parts shown in Fig. 2. Fig. 4 is a top view 25 of the same.

The molded or concrete beam, girder or other structural element is indicated at 6, and the reinforcement is embedded therein at the time said element is molded. This reinforcement consists of a metal bar or beam 7 extending lengthwise through the concrete element and preferably located in the lower part thereof. This bar is bound or tied within the concrete by means of metal loops 8, each of which is formed of a separate rod or piece. The main portion or body of the loop is located above the bar, within the concrete, and the said loops, with respect to the length of the bar, are located on opposite sides thereof alternately, and they also overlap or extend partly over or beyond each other. They are connected at their ends to the bar by being bent around the lower edge thereof, as at 9, and then the 40 ends are inserted crosswise through holes as at 10 in the bar, the ends or extremities of the rods being extended to project outwardly or laterally into the body of the con-

crete, as at 11. The main part or body of the loops is bent outwardly or laterally at the top to lie beyond the vertical plane of the bar and curved to describe a compound curve when viewed from the top, as indicated in Fig. 4. They thus enclose or bind a greater part of the body of the concrete than if they were located in a single vertical plane, and thereby serve to prevent or resist longitudinal split or breakage of the structure along the line of the beam. The structure is further reinforced and strengthened by rods 12, of which there is one on each side, extending longitudinally through or under the crowns of the loops.

A reinforcement so constructed has great strength and binding qualities in proportion to its weight of metal and it may be cheaply constructed, since the reinforcement contains no parts requiring special rolling or manufacture, the bar being preferably a plain flat bar punched properly, and the loops and longitudinal rods being formed of ordinary round stock which can be readily bent to proper shape.

I claim:

1. A reinforcement for concrete structure, comprising a metal bar with holes therein, and a series of separate overlapping loops arranged along and located alternately on opposite sides of the bar, the respective ends of each loop extending through the holes at different points along the bar.

2. A reinforcement for concrete structures, comprising a metal bar, a series of overlapping loops along the same, on opposite sides thereof, and extending outwardly and laterally at the top, and a rod extending lengthwise through the loops on the respective sides of the bar.

In testimony whereof I have signed my name to this specification in the presence of two subscribing witnesses.

GEORGE IBACK.
